UNITED STATES PATENT OFFICE.

DANIEL MCFARLAN MOORE, OF NEWARK, NEW JERSEY, ASSIGNOR TO THE
MOORE ELECTRICAL COMPANY, OF NEW YORK, N. Y.

ELECTRIC LUMINOUS ALPHABET AND BOARD FOR SAME.

SPECIFICATION forming part of Letters Patent No. 602,953, dated April 26, 1898.

Application filed December 17, 1895. Serial No. 572,421. (No model.)

To all whom it may concern:

Be it known that I, DANIEL MCFARLAN MOORE, a citizen of the United States, and a resident of Newark, in the county of Essex 5 and State of New Jersey, have invented a certain new and useful Electric Luminous Alphabet and Board for Same, of which the following is a specification.

My invention relates to the use of electric lighting for decorative and advertising purposes, and has for its object the construction of an apparatus by which the letters of the alphabet, numerals, and ornamental characters and figures may be made to appear as produced by a continuous line of light, or, in fact, to consist of an electric lamp fashioned to represent the desired character instead of being made up of a number of incandescent lamps, as is now the common practice.

In carrying out this invention I employ lamps or illuminating characters constructed and operating substantially as the lamps fully disclosed in patents already granted to me, particularly Patent No. 548,127; and the invention consists, mainly, in the adaptation of these lamps to the purpose above specified.

The invention further consists in the construction, combination, and arrangement of parts hereinafter fully described, and set forth in the claims.

In the accompanying drawings, forming a part of this specification, Figure 1 represents in face view a display or sign board illustrating my invention. Fig. 2 shows an edge view thereof and diagrammatically indicates the manner of supplying the board with current. Figs. 3 and 4 are detail views, on an enlarged scale, showing the construction of the characters and the manner of mounting them upon the board. Fig. 5 is a partially-sectioned side view of the switching apparatus and the interrupters used in connection with the sign-board. Fig. 6 is a plan view of the said apparatus, the cover and interrupter being removed. Fig. 7 is a diagram of the circuits of my apparatus.

Any means of support by which the electric current may be conveyed to the characters to be illuminated may be used, but the one shown has proven the most satisfactory

of any yet tried. It consists of a board or back A, formed of any suitable material, preferably wood, and formed after any conceivable design. Upon this are mounted supporting devices for the characters to be illuminated, which devices must be thoroughly insulated from one another. Upon each end are mounted slotted plates B, in which at one end of the board are adjustably secured the posts C, and at the other end are adjustably secured posts D, through which are passed tension-screws E. To each tension-screw are connected two wires F or the ends of a wire loop, the opposite ends or end of which are secured to one of the posts C. 65

The letters, numerals, or ornamental devices G to be used are formed of tubes of glass or other suitable translucent material and provided with teats H, preferably projecting rearwardly therefrom, as indicated. 70 These teats are for the reception of electrodes which may be removable therefrom or fixed thereon in any convenient manner, preferably by applying conducting-paint thereto. These teats are preferably hollow, though they 75 may be solid, and are inserted between the wires F to hold the characters in place and by their metallic coating to put the characters in circuit. Little loops of wire I or other devices, as spiral springs I', Fig. 3, serving to keep 80 the wires F from spreading, may be placed upon said wires, though the wires may be given sufficient tension to hold the characters in place without said keepers.

Instead of using wires F, as just described, 85 I may, as above stated, use other supporting means—as, for example, a single wire F' at top and bottom of each character, to which metallic cups, as J, may be soldered, the characters being provided with teats at top and 90 bottom removably fitted to said cups, as indicated in Fig. 4, or these cups might be secured to the teats and the letters sprung into place between wires placed side by side horizontally, as indicated in Fig. 4 by dotted circles X. 95

In letters or designs formed of a section of tube, as the "7" and "1," the teats are located at the ends of the section, or in the case of the "V" at the ends and the apex, while in char- 100

acters formed of an endless tube, as the "B," "O," and star, the teats are so located as to divide the tube into two equal or nearly equal branches, so that the illumination of both 5 sides of the character will be uniform. All these letters or characters are readily removable and can be rearranged or exchanged for others at will.

Each tubular character is partially exhausted of air or filled with some other rarefied gas, and when connected in circuit, as 10 above described, becomes in reality an electric lamp operating as described in my Patent No. 548,127, above referred to. The interrupter described in said patent and the 15 necessary switches for controlling and regulating the current are preferably mounted in a little box K upon the back of the board, as indicated in Fig. 2. In one end of this box 20 is placed a socket L for the reception of a plug through which connection may be made to the source of current, the apparatus in the box being connected to said socket. I have so designed said apparatus that it may be 25 used upon the ordinary incandescent circuit, and by means of a connection, as M, having at one end the plug fitting socket L and at the other a plug y, fitting an incandescent-lamp socket, connection may be readily made 30 by taking a lamp from the socket and inserting the plug y in its place, as diagrammatically illustrated in Fig. 2.

In operating the lamps or illuminating characters above described I prefer to employ an interrupter operating substantially 35 as that disclosed in my patents already referred to, though current may be supplied to said lamps or characters in other ways. The interrupter illustrated at N is substantially 40 the same as that set forth in my patent last referred to and consists of a receptacle having the highest possible degree of vacuum and containing an armature a, mounted on a spring having a bias toward a fixed contact b and said 45 spring and contact having leaders extending out through the wall of the receptacle. I preferably make the interrupter N removable, and for that reason terminate the leaders specified with contact-pieces c and d, rigidly mounted upon said receptacle. I also 50 preferably mount the interrupter on the cover of the box and arrange the circuits thereto in a manner such that on raising the cover the circuit will be broken, and thus insure 55 the closure of the box when the apparatus is in operation and dead-circuits when the apparatus is exposed. The interrupter may, however, be mounted in any other position desired. To hold the interrupter in place, it 60 is slipped under or into a band or clasp O, secured to the cover of the box. When in place in said clasp, the contact d rests snugly against a conducting-stop e, secured to the cover, and the contact c engages a spring-contact f, also secured to the cover. This 65 spring also assists in rigidly holding the interrupter in place.

The magnet P, which operates on the armature a, is placed in the bottom of the box and has a core consisting, preferably, of a 70 bundle of wires, which is upturned to bring it into the desired proximity to the armature. An ordinary key-switch Q is located in the box, with its stem protruding, as indicated, so that the circuit may be turned on or off 75 without opening the box. Its contact-springs are indicated at r, between which plays the connector s, the stem being held in its "on" and "off" positions by the springs and squared block shown at T. 80

I also prefer to employ a safety-switch, which may be closed by the key of switch Q and automatically opened should an extra stress of current enter the coil of magnet P. This switch consists of two springs g and h, 85 suitably insulated from one another, as by mounting them upon a block of fiber or vulcanite, as R, which carries the switch Q. On the end of this block is also mounted a spring carrying at its upper end an armature k, which 90 is just out of the normal field of core P'. In this position of armature k contact h rests against the spring thereof and is held thereby in engagement with contact g. When an extra stress of current strikes the coil of magnet P, the armature k is attracted, which allows g to separate from h and interrupt the 95 circuit at that point. The key-stem of switch Q is prolonged beyond the bearing S and has a projection thereon or pin therethrough, as 100 m, by which the spring g may be thrown back to allow the armature k to return to place.

Referring to Figs. 5 to 7, the circuits may be traced as follows: The leading and return circuits being brought from the incandescent 105 circuit or any other source to the socket L, the circuit is continued from the center contact X over conductor 8 to springs g h, thence through bearing S and switch Q to magnet P, thence to contact U on the side of the box. 110 Here the circuit divides and branch g passes by contact V on the cover of the box to spring-contact e, thence through b and the spring of armature a to d and e, thence by a contact W, shown as connected directly to the socket 115 and electrically to the rim thereof, with which the return-circuit connects. The other branch leading from contact U is over conductor 10 to one of the supports or sets of wires F, thence through the illuminating characters G to the other support or set of wires F and to the rim of the socket L. The connections with the support F may be made in any suitable way, one being indicated in Fig. 5, where the wires 10 are shown as confined 120 under the heads of the screws which hold the plates B in place in the board. The apparatus-box is preferably placed at the end of the board, where the adjusting-screws for wires F are located, and the connection of 125 wires 10 made inside the box with the screws, respectively, of the upper and lower supports F. Following the diagram in Fig. 7 it will be seen that the first impulse of current will 130

pass through the magnet and interrupter and that on the break of circuit in the interrupter current will be through the magnet and the illuminating characters with the effect 5 fully disclosed in the patent above referred to. Instead, however, of the circuit passing, as just stated, on the break of circuit in the interrupter connections may be made, as indicated by the dotted lines V, so that it will 10 be only a self-induced current that will traverse the illuminating characters.

In Figs. 5 to 7 I have shown and prefer to use, though not absolutely necessary, a lightning-arrester across the leaders at the point 15 of connection thereof with my apparatus, as indicated at Z, which, as shown, may be located in one corner of the apparatus-box. The part Z also has the function of a spark-arrester in preventing the flow to the lights 20 or to the generator of excessive currents of induction from the apparatus in the box.

Many changes in the construction and arrangement of the various parts of my apparatus as above set forth may be made and 25 any number of characters and variety of designs constructed and used upon the display-board and still be within the domain of my invention.

What I claim as my invention is—

30 1. The combination with the back-piece or board A, of the parallel wires F, stretched across said board and mounted adjustably thereon, suitable tension devices for said wires, and hollow vacuous receptacles provided with electrodes adapted to enter between the parallel wires for holding said receptacles in place, substantially as set forth.

2. The combination with the board or back-piece A, provided with parallel conductors F, 40 adjustable laterally thereon, of illuminating characters consisting of translucent hollow vacuous receptacles provided with hollow rearwardly-extending projections surrounded by electrodes adapted to fit between the conductors F, and hold the receptacles in place, substantially as set forth.

3. An illuminating character consisting of 45 a translucent hollow vacuous receptacle provided with hollow, lateral, rearwardly-extending projections in combination with separated terminals of an electric circuit adapted to removably hold one or more of said

characters, substantially as and for the purpose set forth.

4. The combination with the apparatus-box, 55 of a magnet located therein, and the interrupter secured to the cover of the box in a position such that when the cover is closed, the armature of the interrupter will be placed in the field of the magnet. 60

5. The combination with the apparatus-box, of an interrupter removably mounted on the cover thereof, two contacts mounted on said cover and electrically engaging or connecting with the terminals of the interrupter, and 65 contact-plates located in the box to engage with said contacts when the cover is closed and complete the circuit through the interrupter.

6. The combination with the apparatus-box, 70 of a clasp mounted therein, two contacts also mounted therein adjacent to the clasp, and an interrupter provided with exterior contacts connected to the terminals thereof and adapted to engage with the contacts in the 75 box when the interrupter is inserted in the clasp.

7. The combination with the interrupter and the magnet operating on the armature thereof, of a supplemental armature controlled by said magnet but out of its normal field, a circuit-breaker one member of which normally rests against the latter armature in circuit-closing position but moves therefrom and opens circuit when an extra stress of current flows in the coil of said magnet, and means for simultaneously controlling the circuit of the magnet and said circuit-breaker. 80

8. The combination with the interrupter and the magnet operating it, of another armature out of the normal field of said magnet, a circuit-breaker held normally closed by said armature but adapted to open when the armature is attracted, the key controlling the circuit of the magnet, and a projection 90 on said key for restoring the circuit-breaker to the normal position.

Signed at New York, in the county of New York and State of New York, this 6th day of December, A. D. 1895.

DANIEL MCFARLAN MOORE.
